UNITED STATES PATENT OFFICE.

EUGENE B. ANDES, OF LANCASTER, PENNSYLVANIA.

TOY FIREARM.

Application filed October 8, 1921. Serial No. 505,009.

To all whom it may concern:

Be it known that I, EUGENE B. ANDES, a citizen of the United States, residing at Lancaster, in the county of Lancaster and State 5 of Pennsylvania (my post-office address being 24 North Marshall St.), have invented certain new and useful Improvements in Toy Firearms, of which the following is a specification.

10 The primary object of my invention is to provide a toy firearm in which means are provided for preventing back-fire, flash or splash, which are liable to injure the operator.

15 With this object in view, one form of the invention resides, comprehensively stated, in a toy pistol, or the like, having a cup-shaped hammer-head, for the reception of the paper cap, in combination with an anvil, the anvil 20 and the hammer-head being of differing diameters, so that, when the hammer-head is in a position of impact against the anvil, the side wall of the hammer head is spaced from the perimeter of the anvil.

25 The invention resides, more specifically, in a hammer-head, as recited, provided, on the impact-face thereof, with a central raised portion, forming a groove therearound, facilitating the exit from the cup of the flame, 30 gases, and noise of explosion.

The invention resides, finally, in the precise novel construction, combination, and arrangement of parts of a toy firearm, as will be hereinafter fully described in the specification, summarized in the claims, and illustrated in the accompanying drawing, forming part of this specification and in which like reference-characters denote corresponding parts throughout the several figures.

40 In the drawing, briefly described:

Figure 1 is a view in side elevation of a toy pistol constructed in accordance with one form of my invention;

Figure 2 is a view in side elevation, looking at the inner face of one of the two sections of the pistol, the hammer and the screws for fastening the sections together being shown in section;

Figure 3 is a detached detail view, in end elevation, of the hammer and trigger;

Figure 4 is a view in side elevation of a slightly modified form of my invention; and

Figure 5 is a view in central, vertical, longitudinal section thereof.

Referring, now, in detail, to the drawings, 55 and, first, to Figs. 1 to 3 thereof:

As is customary in the construction of toy pistols, rifles, and like pieces of ordnance made as playthings, my toy pistol is made in sectional form, the sections being cast and 60 united by screws, or otherwise.

My toy firearm may take any one of several forms. As shown, it is in the form of a pistol for exploding paper caps. It comprises two sides or sections, each denoted by 65 the reference-numeral 1, and virtually duplicates of each other. The sections may be united in any one of several ways, as by rivets,—screws 2 being shown in the drawing, passing through registering openings. 70

One of the sections carries the trigger-and-hammer fulcrum-pin 3 and a disk-shaped anvil 4. The anvil, however, may be of other forms than disk-shaped.

My hammer and trigger are formed integral, as usual in toy pistols, the trigger portion being designated by the reference-numeral 5 and the hammer portion by the reference-numeral 6. This combined hammer and trigger is provided with a recess or slot 80 extending inward from one side of the hammer-and-trigger piece (as distinguished from the conventional hole or aperture found in toy-pistol hammer-and-trigger pieces, as customarily constructed), which 85 facilitates casting the hammer-and-trigger piece.

The hammer-portion 6 is peculiarly formed. It is provided with an annular rim or flange 8 projecting forwardly of the 90 pistol, and of a diameter relative to the anvil 4 to provide a space between the rim and anvil when the hammer is in impact position against the anvil. The face of the hammer surrounded by said rim is provided with a raised circular portion 9 concentric with the rim and of smaller diameter than said anvil, providing an explosion chamber 10.

It will be understood that the paper caps 100 are placed within the cup portion of the hammer (and not in a recess in the anvil, as in other constructions,) and the forward-projecting side wall of the explosion-chamber directs the flame and gases of explosion forward,—and not backward onto the hand, clothes and person of the operator, 105 as in other constructions.

Referring, now, in detail to Figs. 4 and 5:

These figures show a construction of pistol, in which the combustion-chamber, instead of being on the hammer, as in the preceding figures, is on the anvil 4'. The anvil is cup-shaped, as shown, and the bottom of the cup is provided with a raised central portion 4^a, forming therearound a groove 4^b. In this form of pistol, the hammer and anvil occupy positions the reverse of those shown in the device of the preceding figures. 6 designates the hammer, and 7 the trigger.

It will be seen that the principle of construction and operation is the same in both forms of my invention.

Having thus fully described my invention, what I claim as new and desire to secure by Letters-Patent is:

1. A toy pistol comprising the combination of an anvil and a hammer, said hammer being provided with a forwardly-projecting marginal flange spaced from the perimeter of said anvil in the position of impact of said hammer, the striking-face of said hammer being provided with a central firing-projection adapted to impinge against said anvil.

2. A toy pistol comprising the combina-

tion of an anvil and a combined trigger and hammer, said hammer being provided with a forwardly-projecting marginal flange spaced from the perimeter of said anvil in the position of impact of the hammer, the striking-face of said hammer being provided with a central firing-projection adapted to impinge against said anvil.

3. A toy pistol comprising the combination of an anvil and a combined trigger and hammer having a fulcrum-pin slot extending inward from one side edge thereof, said hammer being provided with a forwardly-projecting marginal flange spaced from the perimeter of said anvil in the position of impact of the hammer, the striking-face of said hammer being provided with a central firing-projection adapted to impinge against said anvil.

4. A toy pistol comprising the combination of an anvil and a combined trigger and hammer having a fulcrum-pin slot extending inward from one side edge thereof, said hammer being provided with a forwardly-projecting marginal flange spaced from the perimeter of said anvil in the position of impact of the hammer.

In testimony whereof I hereunto affix my signature.

EUGENE B. ANDES.
